Primary Examiner — Jennifer Rivard(74) *Attorney, Agent, or Firm* — Wang Law Firm, Inc.(57) **CLAIM**

The ornamental design for a photocuring machine for nail painting, as shown and described.

DESCRIPTION

FIG. 1 is a perspective view of a photocuring machine for nail painting showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines shown along the top and along the interior illustrate portions of the machine. The broken lines along the arched opening of the machine in FIGS. 1 and 2 illustrate the bounds of the claim. None of the broken lines form part of the claimed design.
